ROBERT J. JAUCH, OF FORT WAYNE, INDIANA, ASSIGNOR TO THE UTILITY STRATE
MFG. CO., OF FORT WAYNE, INDIANA, A CORPORATION

BULLDOZER FOR CHASSIS FRAMES

Application filed March 10, 1927. Serial No. 174,158.

This invention relates to improvements in bulldozers, especially adapted for straightening demolished chassis frames. The object of the invention is the provision of an apparatus that may be readily applied to the chassis frame of an automobile without complete removal of the body or engine portions of the automobile so that the bent frame may be straightened to its original shape expeditiously. Another object is to construct the appliance that it may be applied to a bent chassis frame and manipulated so as to force the bent portion of the frame either outwardly or inwardly to its original shape as may be required.

These objects are accomplished by the construction illustrated in the accompanying drawings, in which:

Fig. 1 is a plan view of an appliance embodying the invention;

Fig. 2 is an end elevation of the same;

Fig. 3 is a cross sectional view of Fig. 1 on the line 3—3 thereof;

Fig. 4 is a front elevation projected from Fig. 2 showing the cross-head portion thereof;

Fig. 5 is a detail view of one of the members of the cross-head shown in Fig. 4; and

Fig. 6 is a similar view of the other member of said cross-head.

The characters appearing in the description refer to parts shown in the drawings and designated thereon by corresponding characters.

The invention consists of a channel beam 1 having a central transverse boss 2 through which extends a jack-screw 3 and in which the screw has threaded relation. On the extending end of the jack-screw is swiveled a cross-head 4 having thereon oppositely disposed hook members 5 that are adjustable relative thereto and removable therefrom, each hook being provided with a set-screw 6 for holding it in adjusted positions on the cross-head.

In connection with the beam 1, upon either side of the jack-screw, is adjustably positioned a cross-head 7, there being a shank 8 extending from the cross-head into the channel beam and a removable pin 9 projecting

through the channel beam and said shank for securing the shank in place. The beam 1 has spaced pin holes 10 made therein so that the shanks may be positioned adjustably relative to the beam.

Each cross-head 7 has mounted in connection therewith a clamp-plate 11 that is provided at each of its ends with a tongue 12 that extends into a groove 13 in the corresponding end of the cross-head 7. A stud 14 projects centrally from the cross-head into an opening 15 in the clamp-plate, and also lugs 16 on the clamp-plate project into a groove 17 in the cross-head, so that the clamp-plate and cross-head are held in alinement with each other. Adjacent each end of the cross-head and of the clamp-plate is provided a stud 18 that projects into the corresponding end of an expansion spring 19 which springs are positioned between the cross-head and clamp-plate and tend to hold the cross-head and plate apart. The cross-head and the plate are shaped so that a space 20 is made between each of their end portions, and the corresponding inner faces of the cross-head and plate have made therein numerous vertically disposed grooves or serrations 21—22. In each end portion of the cross-head 7 and its plate 11 are vertically disposed slots 23, and positioned in the spaces 20 between the cross-head and plate are corresponding grapple members 24, each of which has made therein a horizontally disposed slot 25, there being a bolt 26 for each grapple member that extends through its slot and through the slots in the cross-head and its plate. Each side of that portion of the grapple hook that extends between the cross-head and plate has made therein vertically disposed serrations 21' that interlock with the corresponding serrations in the cross-head and plate so that when the bolts 26 are tightened the grapple members are firmly clamped between the cross-head and plate and held from turning.

In utilizing the invention, when the channel 27 of the chassis frame is to be bent outwardly, the grapple members 24 are disposed with and the hook members 5 are adjustably positioned on the cross-head 4 and into en-

gagement respectively with the top and bottom flanges 28 and 29 of the channel. The members constituted of the cross-heads 7 and their plates 11 are adjusted against the outer face of the channel 27 and the jack-screw is then manipulated so that it moves outwardly in the beam 1. In this maner force is applied to the channel outwardly through the medium of the cross-head 4 and hook members 5 against resisting force of the other cross-heads against which the channel bears.

When the channel is to be bent inwardly, the hook members 5 are dispensed with, and the grapple members are applied to the channel so that the flanges thereof are engaged thereby as in the former instance with respect to the hook members, and the cross-head 4 is adjusted against the outer face of the channel. The jack-screw is then manipulated so that it moves inwardly in the beam 1. In this manner force is applied to the channel inwardly through the medium of the cross-head 4 against resisting force of the grapple members 24.

In performing the operation of bending the channel outwardly, the members 7 may be dispensed with by removing the pins 9 that connect their shanks with the beam, and in their stead ordinary blocks (not shown) of suitable size, may be positioned between the beam 1 and the channel.

By this construction the operation of straightening the bent channel in the chassis frame of an automobile may readily be performed without the necessity of removing completely the body and other parts of the automobile from the channel as it is only necessary to loosen and raise the body from the channel sufficiently to admit of placing the hook members and grapple members in connection with the channel.

A feature of the invention is that the grapple members 24 are independently adjustable relative to each other in their cross-head, and when the securing bolts 26 are tightened are firmly held from turning in the cross-head. The slots 25 in the grapple members and the slots 23 in the cross-head admit of the grapple members being adjustably spaced from each other as well as adjustably extended so as to project from the cross-head independent of each other the required distance to engage the corresponding flange of the chassis frame channel. This is essential, especially when the upper flange and the lower flange of the channel differ in breadth. It is desirable in applying the grapple members and the cross-head 7 to the channel frame that rigidity is established between the cross-head and the grapple members so that unintended pressure or strain is not applied to the channel when force is exerted as when twisting the channel to straighten it, which may be accomplished by applying the cross-heads 7 and their grapple members to the channel

independently of the other parts of the appliance. Thus, one of the cross-heads and its grapple members fitted to the channel at one place may be utilized to sustain the channel, while the other cross-head and its grapple members may be applied to the channel at a point spaced from the former cross-head and manipulated so as to twist the bent channel to its normal state. By snugly fitting the grapple members and their cross-heads to the channel, the tendency of the flanges to become kinked during the straightening operation is greatly lessened.

What I claim is:—

1. In a bulldozer for straightening damaged chassis frames, a recessed beam having a central boss, and spaced pin holes in each end portion; a jack-screw extending through said boss and having threaded relation therewith; a cross-head on the projecting end of the jack-screw and having swivel relation therewith; a pair of hook members removably and adjustably mounted on said cross-head, one on each end portion thereof; a pair of adjustable cross-heads, one in adjustable connection with each end portion of said beam; and a pair of grapple members adjustably mounted in each of said adjustable cross-heads, one in each end portion thereof, there being clamping means provided to prevent turning of the grapple members in their respective cross-heads.

2. In a bulldozer for straightening damaged chassis frames, a beam; a jack-screw extending through said beam and having threaded relation therewith; a cross-head on the projecting end of the jack-screw and having swivel relation therewith; a pair of hooked members adjustably mounted on said cross-head; a pair of cross-head members adjustably and removably positioned in connection with said beam; and a pair of grapple members adjustably secured in each of said cross-head members.

3. In a bulldozer for straightening damaged chassis frames, a beam; a jack-screw extending through said beam and having threaded relation therewith; a cross-head on the projecting end of the jack-screw and having swivel relation therewith; a pair of hooked members adjustably mounted on said cross-head; and a pair of members adjustably and removably positioned in connection with said beam, one on each end portion thereof, each comprising a depending supporting member to which is attached a bar substantially midway of its length.

4. In a bulldozer for straightening damaged chassis frames, a beam; a jack-screw threaded in said beam; a swiveled cross-head on the projecting end of the jack-screw; a pair of hooks adjustably connected to said cross-head and facing each other for engaging the channel of the chassis frame; and a member applicable between each end portion

of the beam and said channel whereby the channel is sustained at corresponding parts thereof when the intermediate portion of the channel engaged by said hooks is drawn outwardly by the action of the jack-screw.

5. In a bulldozer mechanism, a cross-head member having a pair of longitudinal slots, one in each end portion thereof; a clamping plate alined with said member having interlocking relation therewith, there being a space between each end portion of the cross-head and the corresponding end portion of the clamping plate and longitudinal slots in the clamping plate alined with the corresponding slot in the cross-head, the inner faces of the cross-head and clamping plate having longitudinally disposed serrations; expansion means disposed between the cross-head and plate; a pair of grapple members 20 extending in the corresponding spaces and having serrations formed on each side thereof so as to interlock with the serrations on the cross-head and plate, each grapple member having an elongated slot therein; and a bolt 25 for each grapple member extending through the corresponding slots in the cross-head, clamping plate and grapple member whereby said grapple members are adjusted and locked between the cross-head and plate.

30 6. In a bulldozer mechanism, a cross-head member having a pair of longitudinal slots, one in each end portion thereof; a clamping plate alined with said member having interlocking relation therewith, there being a space between each end portion of the cross-head and the corresponding end portion of the clamping plate and longitudinal slots in the clamping plate alined with the corresponding slot in the cross-head, the inner 35 faces of the cross-head and clamping plate having longitudinally disposed serrations; a pair of grapple members extending in the corresponding spaces and having serrations formed on each side thereof so as to interlock 40 with the serrations on the cross-head and plate, each grapple member having an elongated slot therein; and a bolt for each grapple member extending through the corresponding slots in the cross-head, clamping 45 plate and grapple member whereby said grapple members are adjusted and locked between the cross-head and plate.

50 7. In a device of the class described, a member comprising an elongated cross-head having serrations and elongated longitudinally disposed slots, and a pair of grapple members, each having serrations that have interlocking relation with the serrations of the cross-head, and an elongated slot extending 55 in a plane at right angles to the corresponding slot in the cross-head, and a securing bolt for each grapple member extending through the corresponding slots in the cross-head and grapple member.

55 8. In combination with a bulldozer for

straightening damaged chassis frames, means for securely gripping and holding such frames, comprising a cross-head, a pair of gripping members adjustably secured to the cross-head substantially at right angles thereto, a hook on each of said members, said hooks facing each other, means for adjusting each of said members independently in relation to the other, and means for adjusting each of said members independently to locate the hook closer or farther from the cross-head.

70 9. A frame straightener comprising a bar-like main frame, a central engaging head and end engaging heads mounted thereon, said central engaging head being extensible and retractable and including a pressure bar having hook arms longitudinally slidable thereon and said end engaging heads including pressure bars having hook arms longitudinally slidable with respect thereto and extensible relative to the last mentioned pressure bars.

75 In testimony whereof I affix my signature.
